United States Patent Office.

WILLIAM GALLOWAY, OF PHILADELPHIA, PENNSYLVANIA.

Letters Patent No. 101,606, dated April 5, 1870.

IMPROVEMENT IN FASTENINGS FOR FRUIT-JARS.

The Schedule referred to in these Letters Patent and making part of the same.

I, WILLIAM GALLOWAY, of Philadelphia, county of Philadelphia, State of Pennsylvania, have invented an Improvement in Preserving-Jars, of which the following is a specification.

Nature and Object of the Invention.

My invention relates to an improvement in that class of fruit-jars in which pressure is applied to the cover and packing by means of cams connected to bails, which can be turned over the covers of the jars; and

My invention consists in forming, on the peripheries of such cams, flat portions, or the equivalent to the same, so that they may be self-retaining in any position to which they may be turned.

Description of the Accompanying Drawing.

Figure 1 is a side view, partly in section, of the upper portion of a preserving vessel with my improvement;

Figure 2, an exterior view;

Figure 3, a plan view; and

Figures 4 and 5, views illustrating modifications of my invention.

General Description.

A represents the upper portion of a preserving vessel, and *a* its mouth, round the edge of which is fitted a packing-ring, *b*, the cover *B* of the mouth bearing upon this ring.

A yoke or bail, *D*, extends across the top of the vessel, and can be turned or swung laterally in either direction over its cover, its hooked ends catching beneath a shoulder, *e*, formed near the top of the vessel, as shown in fig. 2.

On this yoke a cam, *G*, is hung loosely, so that it can be turned in one direction to depress the cover, and in an opposite direction when the cover has to be relieved from pressure and removed from the vessel's mouth.

I am aware that a cam hung to a yoke has been heretofore used for applying pressure to the cover of a preserving-vessel, over which the bail extends so as to be turned laterally in either direction, but in all such cases the edge of the cam has been made in a continuous curve, so that it became necessary in applying pressure to the cover, to turn it to a definite position, in order to prevent the bail from swinging to one side, and the cam from turning back again and allowing the cover to become loose.

As the packing-rings and the seats for the same vary in different jars, the covers of some jars may require the cams to be turned to a greater extent; hence the improvement of making the cam self-retaining in any position to which it may be adjusted. I accomplish this by forming on the edge of the cam a number of flat places, one or other of which must bear upon the cover when the latter is depressed, so that the rotation of the cam and lateral movement of the bail are prevented, until by a slight effort the cam is turned therefrom, when the cover has to be released from pressure.

The cam *G*, having flat portions *x* on its periphery, and hung to a bail connected to a jar so as to swing or turn laterally over the cover of the latter, as specified.

In testimony whereof I have signed my name to this specification in the presence of two subscribing witnesses.

WM. GALLOWAY.
